CENTERING MEANS FOR RAILWAY DRAFT
DEVICESEdmund P. Kinne and Frank H. Kayler, Alliance,
Ohio, assignors to American Steel Foundries,
Chicago, Ill., a corporation of New Jersey

Application August 12, 1943, Serial No. 498,292

31 Claims. (Cl. 213—19)

1

Our invention relates to a railway draft arrangement and especially to novel buffering and drafting means designed to be associated with a coupler of the type described in detail in Patent 2,271,770, issued by the United States Patent Office on February 3, 1942, to Edmund P. Kinne.

The general object of our invention is to devise a draft arrangement for such a coupler incorporating features for centering the coupler and holding it level without the use of separate carrier means.

Our novel arrangement incorporates front and rear followers with resilient means compressed therebetween and auxiliary resilient means so arranged as to maintain the coupler in its normal position or to return it to normal position upon horizontal or vertical angling therefrom.

Our novel structure also contemplates an arrangement wherein the centering and leveling device for the coupler may be used without resilient drafting means, if desired.

In the drawings, Figure 1 is a top plan view of our novel form of draft arrangement shown as applied between the draft sills of a car structure (otherwise not shown).

Figure 2 is a side elevation, partly in section, of the structure shown in Figure 1, the section being taken approximately in the vertical longitudinal plane indicated by the line 2—2 of Figure 1.

Figure 3 is a fragmentary view corresponding to the showing of Figure 1 but illustrating a horizontal angling of the coupler.

Figure 4 is a fragmentary view corresponding to a portion of Figure 2 while illustrating vertical angling.

Figure 5 is a sectional view through the draft connection, the section being taken in the vertical transverse plane indicated by the line 5—5 of Figure 2.

Figures 6 to 9 inclusive are views of our novel form of connecting bolt, Figure 6 being a top plan view with a portion of the stem cut away, Figure 7 a side elevation, Figure 8 an end view taken from the left as seen in Figures 6 and 7, and Figure 9 a sectional view through the pin opening, the section being taken approximately in the horizontal plane bisecting the pin opening and as indicated by the line 9—9 of Figure 7.

Figures 10 to 12 inclusive show in detail my novel form of bearing block, Figure 10 being a top plan, Figure 11 a front elevation taken from the right as seen in Figure 10, and Figure 12 a side elevation taken from the bottom as seen in Figure 10.

2

Describing the structure in detail, our novel arrangement comprises the spaced sills 2, 2, forming a portion of a car body (not shown), said sills comprising the rear draft lugs 4, 4 and the front draft lugs 6, 6 of usual type. Seated respectively against said front and rear lugs may be the front follower 8 and the rear follower 10 with the compression spring 12 confined therebetween. Bearing against the front follower 8 may be the butt end 14 of the coupler 16, said butt end having a flat vertically arranged central face, seating as at 18 against the front follower 8 and having vertical arcuate portions at either side of said flat face, and seating as at 20, 20 against the vertical ribs or shoulders 22, 22 (Figure 3), said shoulders having surfaces complementary to the adjacent portions of said coupler butt in order to accommodate its seating thereagainst. The shank or butt portion 14 of the coupler 16 is formed with a horizontal slot 23, flaring at both ends as well shown in the sectional view of Figure 2, within which may be received the relatively flat head portion 24 of the tail bolt, generally designated 26, said head portion being horizontally tapered as at 27, 27 fore and aft of the pivot point 28 as well seen in the side view of Figure 7 to accommodate the head 24 in the slot 23 in vertical angling of the coupler. The head 24 may be formed with a vertical pin opening 30 through which may pass the pivot pin 32 (Figure 2), said pivot pin also extending through the vertically aligned openings 34, 34 formed in the shank or butt 14. The rear wall of the tail bolt pin opening 30 may be tapered above and below the horizontal axis of said bolt as seen at 36, 36 (Figure 7) to accommodate said vertical angling and the forward wall of said opening 30 may be cut away as at 38 (Figure 9) to form an arcuate seat for the bearing block, generally designated 40 (Figure 10), which may seat as at 42 against the pivot pin 32 and as at 44 against the beforementioned recess at 38, said block 40 thus accommodating horizontal and vertical angling of the coupler with respect to the tail bolt 26.

45 The bolt 26 may extend through the central opening 46 in the front follower which may be reinforced by the annular flange or boss 48, affording positioning means for the main compression spring 12. The said bolt 26 may also extend through the central opening 50 in the rear follower 10 which may afford a seat as at 52 for said spring 12. The opening at 50 may be large enough to accommodate the boss 54 formed on the inner end of the securing nut 56, said nut 56 being spaced rearwardly of the rear follower 10.

and providing a lost-motion connection between the bolt 26 and the followers. The boss 54 affords on its inner end an annular seat as at 58 for the inner spring 60 which is thus compressed between said securing nut 56 and the front follower 8. It will be understood that this inner spring 60, applied under pressure between the front follower boss 48 and the nut 56, exerts a force to hold the coupler butt 14 against the front follower, seated at 18, 20, and resists any angular movement of said coupler, whether vertical or horizontal within the period of lost motion between bolt 26 and the followers.

In Figure 3 is illustrated the condition that takes place under horizontal angling wherein it may be noted that the coupler butt 14 is fulcrumed as at 62 against the face of the front follower 8, a corner radius of the coupler shank being seated against said front follower at one side of the center line of the gear. This angling action has further compressed the center spring 60 due to the pulling of the tail bolt in a forward direction so that the securing nut 56 is seated as at 64 against the rear follower 10. The expansive force of the spring 60 thus is operative to return the coupler to its normal central position as illustrated in Figure 1.

The condition which occurs upon vertical angling is illustrated in Figure 4. Here the coupler is angled downwardly and the extension 66 on the lower rear edge of the coupler butt is fulcrumed as at 68 against the front follower 8 while the bolt 26 is again pulled forward so that the nut 56 is in close proximity as at 70 to the rear follower 10. As in the condition of Figure 3, the auxiliary spring 60 is compressed and the expansive force of said spring exerts pressure to pull the coupler butt back into full engagement with the front follower, as illustrated in Figure 2.

From the above description, it will be apparent that the action of the centering and leveling means is independent of the main compression or draft spring 12 and, if desired, the centering and leveling device may be used independently of the draft spring. In other words, if desired, the draft spring may be omitted entirely. In such case, the front follower 8 would be a fixed member instead of a movable member and the draft spring 12 would be replaced by a rigid member of length equal to the solid height of said spring 12.

The detail of the tail bolt is shown in Figures 6 to 9 inclusive, wherein it may be noted that the threaded end 72 may be slotted as at 74 to accommodate the retaining bolt 76 (Figure 2) which may hold the nut 56 against rotation of said bolt and permit adjustable positioning thereof.

The pin bearing block 40 is shown in detail in Figures 10 to 12 inclusive and may be seen to be of arcuate form with the cylindrical face 42 on its inner radius for full bearing against the pivot pin 32, said block presenting at its outer radius a spherical seat as at 44 for bearing against the complementary base on the head of the tail bolt as at 38, as already described.

It will thus be seen that in our novel arrangement we have provided resilient means for accommodating both vertical and lateral angling of the coupler in normal use thereof while at the same time maintaining said coupler in horizontal position where service conditions permit.

It is to be understood that we do not wish to be limited by the exact embodiment of the device shown, which is merely by way of illustration and not limitation as various and other forms

of the device will, of course, be apparent to those skilled in the art without departing from the spirit of the invention or the scope of the claims.

We claim:

5 1. In a draft arrangement, front and rear followers designed to be confined between front and rear draft lugs of an associated car body, main resilient means compressed between said followers, a coupler seated against said front follower, a draft bar pivotally connected to said coupler and extending through said followers, securing means fixed on the end of said draft bar and having a portion extending through said rear follower, and auxiliary resilient means compressed between said portion and said front follower and acting to urge said coupler into engagement therewith, said coupler having a butt with a flat face merging at opposite vertical edges thereof into arcuate shoulders, and said front follower having a face complementary in form for seating of said butt and affording a fulcrum against which said shoulders may pivot upon lateral angling of said coupler.

2. In a draft arrangement, spaced followers 25 adapted to seat against confining draft lugs, a coil spring compressed therebetween, a coupler, a draft rod pivotally connected to said coupler and extending through said followers, and securing means on the end of said draft rod, said securing means having a shank extending through the adjacent follower and affording a spring seat, and an auxiliary spring compressed between said seat and said front follower, said auxiliary spring acting to retain the shank of said coupler seated 30 against said front follower, said coupler pivoting against said front follower upon lateral angling and upon vertical angling with respect thereto.

3. In a draft arrangement, spaced followers 35 adapted to seat against confining draft lugs, a coil spring compressed therebetween, a coupler having normal flat face engagement with one of said followers, a draft rod pivotally connected to said coupler and extending through said followers, and securing means on the end of said draft rod, said securing means having a shank extending through the adjacent follower and affording a spring seat, and an auxiliary spring compressed between said seat and said front follower, said auxiliary spring acting to retain the shank of 40 said coupler seated against said front follower, said coupler pivoting against said front follower upon lateral angling with respect thereto.

4. In a draft arrangement, a coupler having a slotted shank, a draft rod having a relatively flat 45 head receivable in said slot, a draft pin pivotally connecting said rod and said shank, said head and slot being horizontally tapered in reverse directions fore and aft of said pivot point to accommodate vertical angling therebetween, and a pivot pin bearing block having a spherical seat in complementary engagement with said head and a cylindrical seat against said pin, the pivot opening in said head having a rear wall tapered vertically above and below the axis thereof to accommodate vertical angling of said coupler and pin with respect to said rod.

5. In a draft arrangement, a coupler having a shank with a slot, a draft rod having a relatively flat head receivable in said slot, a universal 50 connection between said rod and said shank and including a cylindrical draft pin pivotally connecting said rod and said shank, said head and slot being horizontally tapered in reverse directions fore and aft of said pivot point to accommodate vertical angling therebetween, and a

pivot pin bearing block having a spherical seat in complementary engagement with said head and a cylindrical seat against said pin, said block rotating about said pin during relative horizontal angling movement between said rod and pin.

6. In a draft arrangement, front and rear followers, main resilient means under compression between said followers, a coupler having a shank with a slot, a draft rod extending through said followers for connection to securing means at one end thereof and into said slot at the other end thereof, a universal connection between said shank and said other end of said rod permitting vertical and horizontal angling therebetween and including a pivot pin extending through said shank and said rod connecting the same, pivot means within said slot between said rod and pin, and auxiliary resilient means compressed between said front follower and said securing means, said coupler fulcruming against said front follower during vertical and horizontal angling thereof, said securing means having a portion extending through said rear follower for reciprocal movement relative thereto.

7. In a draft arrangement, front and rear followers, main resilient means under compression between said followers, a coupler, a draft rod extending through said followers and pivotally connected at one end thereof to said coupler, said pivotal connection providing for lateral and vertical angling of said coupler with respect to said rod, and securing means on the end of said rod remote from said coupler, said securing means having a shank extending through the adjacent follower and affording a spring seat, and an auxiliary spring compressed between said seat and said front follower, said coupler fulcruming against said front follower upon lateral or vertical angling thereof.

8. In a draft arrangement, front and rear followers, main resilient means compressed between said followers, a coupler having a slotted shank, a draft rod extending through said followers and into said slot, a pivot pin connecting said rod and said shank, a bearing block in engagement with said rod and pin, securing means adjustably fixed on said draft rod remote from said coupler, said securing means having a portion extending through said rear follower, and auxiliary resilient means compressed between said portion and said front follower, said coupler fulcruming against said front follower upon vertical and horizontal angling with respect thereto.

9. In a draft arrangement, front and rear followers, main resilient means compressed between said followers, a coupler having a slotted shank, a draft rod extending through said followers and into said slot, universal coupling means connecting said rod and said shank within said slot and permitting lateral and vertical angling of said coupler with respect to said rod, securing means adjustably fixed on the end of said rod remote from said coupler, and auxiliary resilient means compressed between said securing means and said front follower, said coupler fulcruming against said front follower upon lateral or vertical angling thereof, said securing means having a portion extending through said rear follower for reciprocal movement relative thereto.

10. In a draft arrangement for a railway car, front and rear followers, resilient means under compression between said followers, a coupler having a shank with an elongate slot, said shank being in normal flat face engagement with said front follower, a draft rod extending through

said followers for connection to securing means at one end thereof and into said slot at the other end thereof, and universal coupling means securing said rod within said slot, said means permitting angling of said coupler relative to said rod in both lateral and vertical directions, said coupler fulcruming against said front follower during vertical and lateral angling thereof.

11. In a draft arrangement, a coupler having a shank with a slot, a draft member having a head receivable in said slot, and universal coupling means securing said member within said slot for permitting lateral and vertical angling of said coupler relative to said member and including a cylindrical draft pin connecting said head and shank, and a draft pin bearing block having a spherical seat in complementary engagement with said head and a cylindrical seat against said pin, said block rotating with said head about said pin during horizontal angling of said coupler relative to said member, said head and slot being horizontally tapered in reverse directions fore and aft of said draft pin to accommodate vertical angling therebetween.

12. In a draft arrangement, a coupler having a shank with a slot, a draft member having a head receivable in said slot, and universal coupling means securing said member within said slot for permitting lateral and vertical angling of said coupler relative to said member, said means comprising a cylindrical draft pin connecting said head and shank, and a pivot pin bearing block having a spherical seat in complementary engagement with said head and a cylindrical seat against said pin, said block rotating with said head about said pin during horizontal angling of said coupler relative to said member.

13. In a draft arrangement, a coupler having a shank with a slot therein, a draft member having a head receivable in said slot, and universal coupling means securing said member within said slot for permitting lateral and vertical angling of said coupler relative to said member, said means comprising a cylindrical draft pin connecting said head and shank, and a pivot pin bearing block having a spherical seat in complementary engagement with said head and a cylindrical seat against said pin, said block rotating with said head about said pin during horizontal angling of said coupler relative to said member, the pivot opening in said head having a rear wall tapered vertically above and below the axis thereof to accommodate vertical angling of said coupler and pin with respect to said draft member.

14. In a draft arrangement, a coupler having a shank with a slot, a draft member extending within said slot, and a universal connection securing said member within said slot for permitting horizontal and lateral angling of said coupler relative to said member, said universal connection including a cylindrical pivot member connecting said draft member and shank, a block between said pivot member and said draft member in spherical engagement with said draft member and in cylindrical engagement with said pivot member, said block rotating with said draft member about said pivot member during one of said angling movements of said coupler relative to said draft member.

15. In a draft arrangement, a coupler having a shank with a slot, a draft member extending within said slot, a universal connection between said member and said shank and including a cy-

cylindrical pivot member connected to said shank and securing said member within said slot, and pivot means disposed between said members in spaced relationship to said shank and having spherical engagement with said draft member and cylindrical engagement with said pivot member and cooperative therewith for accommodating vertical and lateral angling of said coupler relative to said draft member.

16. In a draft arrangement, an elongate draft member having a head portion with a pivot pin opening, said head portion having the top and bottom faces thereof longitudinally tapered fore and aft of said opening, a pivot pin received within said opening, said opening having a rear wall tapered vertically above and below the axis thereof for engagement with said pin and a front wall having a spherical surface, and a pivot pin bearing block in said opening and having complementary engagement with said surface and cylindrical engagement with said pin.

17. In a draft arrangement, an elongated draft member having a head portion with a pivot pin opening, a pivot pin received within said opening, said opening having a rear wall tapered vertically above and below the axis thereof for engagement with said pin and a front wall having a spherical surface, and a pivot pin bearing block in said opening and having complementary engagement with said surface and cylindrical engagement with said pin.

18. In a draft arrangement, an elongate draft member having a head portion with a pivot pin opening, a pivot pin received within said opening, said opening having a rear wall tapered on opposite sides of the axis thereof for engagement with said pin and a front wall having a spherical surface, and a pivot pin bearing block in said opening and having complementary engagement with said surface and cylindrical engagement with said pin.

19. In a draft arrangement, spaced followers adapted to seat against confining draft lugs, a coil spring compressed therebetween, a coupler, a draft rod extending through said followers and having a single universal connection at one end thereof to said coupler, said universal connection permitting horizontal and vertical angling of said coupler relative to said rod, and securing means on the end of said draft rod, said securing means having a shank extending through the adjacent follower and forming a spring seat, and an auxiliary spring compressed between said seat and the remote follower and acting to urge said coupler into engagement therewith, said coupler pivoting against said last-mentioned follower upon vertical or lateral angling with respect thereto, said angling being operative to compress said auxiliary spring and cause reciprocal movement of said draft rod with respect to both said followers.

20. In a draft arrangement for a railway car, spaced sills with draft lugs, front and rear followers confined therebetween, resilient means under compression between said followers, a coupler having a shank with a horizontal elongate slot, a draft bolt having a relatively flat head receivable in said slot, a draft pin pivotally connecting said rod and shank for accommodating horizontal angling of said coupler with respect to said draft bolt, said head and slot being horizontally tapered in reverse directions fore and aft of said pivot point to accommodate vertical angling therebetween, a pivot pin bearing block having a spherical seat in complementary engage-

ment with said head and a cylindrical seat engaging said pin, the pivot opening in said head having a vertical wall tapered vertically above and below the axis thereof to accommodate vertical angling of said coupler and pin with respect to said bolt, said draft bolt extending through said followers for connection to adjustable securing means and said front follower, said coupler fulcruming against said front follower upon horizontal or vertical angling thereof, said securing means having a portion extending through said rear follower for reciprocal movement with respect thereto, said securing means having stop means for seating against said rear follower and limiting said reciprocal movement.

21. In a draft arrangement for a railway car, spaced sills with draft lugs, front and rear followers confined therebetween, a coil spring under compression between said followers, a coupler, a draft bolt extending through said followers for connection to adjustable securing means, a universal connection between said coupler and said bolt including a pivot pin connecting said coupler to one end of said bolt and permitting horizontal angling of said coupler relative to said bolt, a pin bearing block engaging said pin and bolt and permitting vertical angling of said coupler relative to said bolt, and a coil spring compressed between said securing means and said front follower, said coupler fulcruming against said front follower upon horizontal or vertical angling thereof, said securing means having a portion extending through said rear follower for reciprocal movement with respect thereto.

22. In a draft arrangement, front and rear followers adapted to seat against confining draft lugs, a coil spring compressed therebetween, a coupler, a draft rod extending through said followers and having a single universal connection at one end thereof to said coupler, said universal connection permitting horizontal and vertical angling of said coupler relative to said rod, and securing means on the other end of said draft rod, said securing means having a shank extending through said rear follower and affording a spring seat, and an auxiliary spring compressed between said seat and said front follower, said coupler pivoting against said front follower upon vertical or lateral angling with respect thereto.

23. In a draft arrangement for a railway car, spaced sills with draft lugs, front and rear followers confined therebetween, a coil spring under compression between said followers, a coupler having normal flat face engagement with said front follower, a draft bolt extending through said followers for connection to adjustable securing means at one end thereof, a single universal connection between the other end of said bolt and said coupler permitting horizontal and vertical angling of said coupler relative to said bolt, and a coil spring compressed between said securing means and said front follower, said coupler fulcruming against said front follower upon horizontal or vertical angling thereof.

24. In a draft arrangement, spaced followers adapted to seat against confining draft lugs, a coil spring in engagement with said followers and under compression therebetween, a coupler having a shank with a slot therein, a draft rod extending through said followers and into said slot, a universal connection between said head and said shank and including pivot means securing said rod within said slot, said universal connection permitting horizontal and vertical angling.

of said coupler relative to said rod, and securing means on the end of said draft rod remote from said coupler, said securing means having a portion extending through the adjacent follower and affording a spring seat, and an auxiliary spring compressed between said seat and the follower remote from said portion, said coupler being arranged to fulcrum during horizontal or vertical angling thereof against the adjacent follower solely against the compressive resistance of said auxiliary spring.

25. In a draft arrangement for a railway car, a car body having draft sills, front and rear followers confined therebetween, resilient means under compression between said followers, a coupler having a shank in normal flat face engagement with said front follower, a draft bolt, a single universal connection between one end of said bolt and said shank, said universal connection permitting horizontal and vertical angling of said coupler relative to said bolt, said draft bolt extending through said followers, and securing means adjustably fixed on said draft bolt remote from said coupler.

26. In a draft arrangement, front and rear followers adapted to seat against confining draft lugs, a coil spring under compression between said followers, a coupler in normal flat face engagement with said front follower and having a shank, a draft rod, a universal connection between said draft rod and shank permitting horizontal and vertical angling of said coupler with respect to said rod and including an elongate slot in said shank, a relatively flat head on said rod in said slot, a cylindrical draft pin pivotally connecting said head and shank, said head and slot being horizontally tapered in reverse directions fore and aft of said pivot point, a pivot pin bearing block having a spherical seat in complementary engagement with said head and a cylindrical seat against said pin, said block rotating about said pin during horizontal angling of said coupler relative to said rod, the pivot opening in said head having a rear wall tapered above and below the axis thereof for accommodating vertical angling of said coupler relative to said draft rod, said block being adaptable to slide upon said spherical seat during vertical angling of said coupler relative to said rod, said coupler during vertical and horizontal angling thereof fulcruming against said front follower.

27. In a draft arrangement, spaced abutment means designed to be confined between spaced draft lugs on an associated vehicle, main resilient means reacting against said abutment means, a coupler, a draft member extending through said abutment means, a universal connection between said coupler and one end of said draft member accommodating vertical and horizontal angling of said coupler with respect to said draft member, securing means on the other end of said draft member reciprocal through one of said abutment means, and auxiliary resilient means reacting against said securing means and the other of said abutment means to urge said coupler into engagement therewith, said coupler and said other abutment means being formed and arranged to cause said coupler to fulcrum against said other abutment means upon vertical or horizontal angling of said coupler against the reaction of said auxiliary resilient means accompanied by reciprocation of said draft member and said securing means through said one abutment means.

28. In a draft arrangement, a coupler having a shank with an opening, a draft member having

a head received within said opening, a universal connection between said coupler and said head permitting angling of said coupler in a plurality of angularly related planes relative to said draft member, said connection including a pivot element extending through a pivot opening in said head and through aligned openings in said shank, a block within said pivot opening at one side of said element and in alignment with the axis of said draft member and having a spherical seat in complementary engagement with said head and a cylindrical seat bearing against the adjacent side of said pivot element, said pivot opening being provided with reversely tapered surfaces on a side thereof remote from said block, said surfaces converging transaxially of said element toward the same.

29. In a draft arrangement, a coupler having a shank with an opening therein, a draft member having a head received within said opening, a universal connection between said coupler and head permitting angling of said coupler in a plurality of angularly related planes relative to said member, said connection comprising a pivot element connected to said shank and extending through an opening in said head arranged transversely of the longitudinal axis of said draft member, a block within said last-named opening interposed between said head and one side of said element and in complementary spherical face engagement with the former and in cylindrical face engagement with the latter, said last-named opening being provided at the opposite side of said element with surfaces extending from opposite ends of said last-named opening and converging transversely of said opening toward said element to accommodate, through a sliding action of said block against said head, angling of said element and thus said coupler in one of said planes.

30. In a draft arrangement, spaced followers, resilient means interposed between and reacting against said followers, a draft member having a lost-motion connection with said followers, a coupler seated against one of said followers, a universal connection between said coupler and member accommodating angling of said coupler in a plurality of angularly related planes, and auxiliary resilient means operatively associated with and reacting against said member and said one follower for urging said coupler into engagement therewith, said coupler, when angling, pivoting against said one follower against the reaction of said auxiliary resilient means within the period of lost motion between said member and followers.

31. In a draft arrangement for a railway car, front and rear followers, resilient means under compression between said followers, a coupler, a draft bolt extending through said followers, a lost-motion connection between said bolt and said rear follower, a universal connection between said coupler and bolt accommodating angling of said coupler in a plurality of angularly related planes, and auxiliary resilient means operatively associated with said front followers and said bolt for urging said coupler against said front follower, said coupler, upon angling, pivoting on said front follower against the reactive resistance of said auxiliary resilient means through said bolt.
